CLAIM

The ornamental design for a storage media chassis, as shown and described.

DESCRIPTION

FIG. 1 is a front left perspective view of a storage media chassis according to a first embodiment of our design; FIG. 2 is a top view of the storage media chassis according to the first embodiment; FIG. 3 is a bottom view of the storage media chassis according to the first embodiment; FIG. 4 is a front elevation view of the storage media chassis according to the first embodiment; FIG. 5 is a back elevation view of the storage media chassis according to the first embodiment; FIG. 6 is a right side elevation view of the storage media chassis according to the first embodiment; and, FIG. 7 is a left side elevation view of the storage media chassis according to the first embodiment. Throughout the Figures, if and where shown: the broken lines showing additional structure of the storage media chassis form no part of the claimed design.

1 Claim, 5 Drawing Sheets
